CARD GAME INDICATOR

Herbert E. Kinnee, Detroit, Mich.

Application April 28, 1937, Serial No. 139,440

2 Claims. (Cl. 273—148)

My invention relates to card games, and its principal object is to provide a game in which a game board provided with a rotating-dial apparatus is used in conjunction with the usual deck of playing cards in such manner that the sequence of the game is broken at frequent intervals so that superior skill on the part of certain of the players is neutralized to a considerable extent. By this arrangement, the game is rendered more social and enjoyable since all of the players have more nearly the same chance of winning.

Another object of my said invention is to provide a game board and apparatus therefore which is simple in construction and economical to manufacture, and which presents very attractive features from a sales stand-point.

With these and other objects in view, I will now describe a preferred embodiment of my invention with reference to the accompanying drawing, in which—

Figure 1 is a plan view of a conventional card table having my improved dial apparatus applied thereto.

Figure 2 is a fragmentary transverse sectional view of the same taken upon the center line, illustrating the construction of the table and the method of mounting the moving dial thereupon.

Figure 3 is a plan view of the dial removed from the table.

Figure 4 is a fragmentary transverse sectional view, corresponding to Figure 2, but drawn to an enlarged scale and showing details of the dial centering and rotating means, and

Figure 5 is a plan view of a washer constituting an element of the invention.

Like characters designate corresponding parts throughout the several views.

1 is the table proper, of well known construction, and 1A is a top member formed of wood, leather, "fabricoid", or any suitable material. 1B is a member positioned intermediate the table and the cover and having therein a central space 1C adapted to rotatably receive the dial D which may also be made from various materials according to the quality and price of the apparatus desired.

In the center of the table is a knob or hand-wheel E having a knurled or serrated periphery and provided with a stem E' which extends downwardly through the top member 1A and is secured to the dial D for the purpose of rotating the same. The opening in the member 1A through which the stem E' passes has an eyelet or grommet G which serves the purpose of a bearing

for the stem E', and in order to establish driving means between the stem and the dial D, the lower end of the stem is squared as at E2 so as to engage a square hole F' in a washer F, shown in plan view in Figure 5, which is secured within a recess in the face of the dial by means of hooks or claws F2 pressed into the material of the same. The dial is further secured upon the stem by a washer H fitted upon the lower end of the latter and secured in position by riveting or other means.

Upon the table top 1A is marked off a circular space S which is divided into eight equal divisions by the radial lines R. The upper five of these divisions, as shown in Figure 1, are marked with the letters A, K, Q, J, and A-K, which stand for ace, king, queen, jack and ace-king respectively. The lower three spaces reading from left to right are marked "Kitty", "Same Suit", and "Dummy" respectively. Within the five upper spaces, and coincident with the letters above mentioned are a corresponding number of openings O in the top through which may be seen at one time five of a set of eight indicia I upon the dial D which represent various suits of the cards, as shown in Figure 3. In the lower central space, opposite which the "Banker" sits as noted by the letter B, is an opening J through which may be seen one of eight equally spaced sets of indicia L upon the dial, each of these sets representing a group of three cards such as 2-3-4 4-5-6, ace-king-queen, etc. In the spaces marked "Kitty" and "Dummy" are openings M, M' through which may be seen at the same time two of eight sets of indicia P which are marked "No" and "Yes" indiscriminately as shown in Figure 3. In the lower central space and close to the hand-wheel E is an opening J' through which may be seen one of three sets of indicia T, each of which consists of the letters PCL or PCR, meaning "Pass cards left" and "Pass cards right" respectively.

In one method of playing the game, each player contributes a chip to each of the eight divisions. The "Banker" deals out all the cards, with an extra hand for himself and with one card which may be called "X" placed face downward in the division marked "Dummy". This latter card is not touched until the end of the hand.

The dealer then turns the disc D in the direction of the arrow Y through one-eighth of a revolution, which changes the respective suits of the "pay" cards as will be indicated through the openings O, and which also may change the words "No" and "Yes" as seen through the openings M, M'.

After the dealer looks at the hand at his right, he may decide if he wish to keep that one or to use the other, or extra, hand. He is not permitted, however, to look at both hands before deciding to keep the first one. If he keeps the first hand, he must auction the extra one to the highest bidder.

The person on the left of the dealer plays the lowest card in his hand at the same time naming it, and others continue to play consecutively higher cards in the same suit until stopped by running out of the suit. The last player then starts with his lowest card in another color, that is, if a red card was the last card played, he must start with the lowest black card in his hand. If he is unable to change color, the play passes to the next person. If at any time all players hold all one color, the last player leads lowest card in the other suit of the same color. As fast as the cards matching those in the layout, as shown through the various openings, are got rid of in playing, each holder collects all the chips in that division of the layout for which he holds corresponding cards.

An important feature of the game resides in playing as quickly as possible, and failure to collect chips before the next card is played causes the holder to forfeit them, and they are left remaining on the board until the next hand. The person going out first collects all chips in the space marked "Kitty" if the word "Yes" appears thereon. If the word "No" appears, the chips remain on the board. The person going out first also collects one chip for each card held by the other players.

If the word "Yes" appears in the space marked "Dummy", the card "X" is turned up and the person holding the matching card in the opposite suit collects the chips. For example, if the card turned up is ten of diamonds, the person holding the ten of hearts collects the chips.

In order to clear the board at the end of a game, the "Banker" deals one card, face upwards, to each player. The one holding the highest card collects the chips in the division to the left of the "Banker" marked "Jack", if no chips are in that division he collects from first space containing chips. The "Banker" then deals one card to each player as before. The holder of the highest card collects the chips in the next space and so on until the chips in all the divisions are collected, including those marked "Dummy" and "Kitty". The "Banker" then divides the chips in the "ace-king" division into halves, and in the space marked "Same suit" into thirds. The "pay" cards are indicated by the suit shown in the space above the "ace-king" division.

The "Banker" again deals one card, face up,

to each player for the last time, and the holders of cards corresponding to those in the "ace-king" division and in the opening J collect the chips.

The game may be played by any number of players from two to seven.

While I have herein described and shown a preferred embodiment of my invention, it will be readily understood that the same may be modified in various ways without departing from the spirit of my invention as defined in the appended 10 claims.

Having thus described my said invention, what I claim and desire to secure by Letters Patent of the United States is:

1. A card game indicator comprising a board, 15 a cover sheet for said board having a circular area divided by radial lines to provide a plurality of segmental spaces, certain of said spaces having therein indicia representing certain cards of suits of a deck of cards, said cover sheet having 20 openings therein each located in a segmental space in radial alignment with the indicia in the space, and a dial rotatably mounted between the board and the cover sheet under said circular area concentric thereto, said dial having 25 thereon pip-markings of suits of a deck of cards, said markings being spaced from each other along a circular path concentric to the dial in position to be displayed through the openings of the cover sheet, said cover sheet having other openings 30 disposed out of annular alignment with the first openings, and said dial bearing indicia disposed in position to be displayed through the last mentioned openings of the cover sheet.

2. An indicator comprising a board, a cover 35 sheet for said board having a circular area divided into segmental areas each having a sight opening therein and bearing indicia, a dial between said board and cover sheet disposed under said circular area concentric thereto and bearing 40 indicia disposed in position to be successively displayed through the sight openings when the dial is turned, said cover sheet having a circular opening at its center and said dial having a central opening of non-circular outline, an eyelet 45 secured through the opening of said cover sheet and constituting a bearing, washers against upper and lower faces of said dial about the opening thereof and having openings registering with the opening of the dial, the upper washer having 50 spurs embedded in the dial, a stem for said dial rotatably passing through said eyelet and having a reduced lower end portion conforming in cross section to the outline of the opening in the dial and snugly engaged through the registering openings of the dial and washers and upset at its lower end, and a turning knob at the upper end of said stem.

HERBERT E. KINNEE.
